UNITED STATES PATENT OFFICE.

FRED M. CARROLL, OF ENDICOTT, NEW YORK, ASSIGNOR TO THE TABULATING MACHINE COMPANY, OF ENDICOTT, NEW YORK, A CORPORATION OF NEW JERSEY.

SENSING MEANS FOR PERFORATED RECORD CARDS.

Original application filed November 18, 1922, Serial No. 601,931. Divided and this application filed December 6, 1923. Serial No. 678,898.

The present invention is directed to the general end of providing means for the placing of a greater amount of statistical or like data on a record without increasing the size 5 of the record and to the provision of means for sensing or reading the same in a record card controlled apparatus.

Heretofore in machines of the Hollerith type, for example, it has been the practice 10 to provide record cards with index points thereon arranged in columns and with the index point positions all laterally spaced from each other and arranged in transverse rows.

15 According to the present invention a record card is provided in which the index point positions of one column overlap the column containing the adjacent index point positions. In this way a greater quantity 20 of perforated data may be placed upon a record without increasing the size thereof or if it is desired to decrease the size of the record the existing amount of data may be retained or even increased.

25 The object of this invention resides in the provision of suitable sensing means for deriving the data from a record card of the character just described.

In the drawings,
30 Figure 1 is a plan view of a record card having improved arrangement of index point positions and perforations thereon.

Figure 2 is a sectional view of one form 35 of sensing means for deriving the data from the perforated record cards.

Figure 3 is an elevation view of record 40 sensing means shown in Fig. 2.

Figures 4 and 5 are similar views of a modified form of sensing means.

45 In more detail the record card 10 is of a form commonly used in this art and comprises a plurality of rows of index point designations 11. These index point designations are preferably printed upon the card and are arranged in a number of parallel vertical columns as shown. The index points are also arranged in transverse rows. Heretofore it has been the practice to place the index point positions of a given value in a 50 single straight line. In order to bring these positions more closely together this would result in adjacent perforations overrunning each other or approaching so closely as to weaken the card. In order to overcome this

difficulty I have placed the index points of 55 a given value in two rows so that the index point positions may be displaced vertically as well as laterally thus permitting lateral overlapping of the adjacent index point position without causing two adjacent perforations of like value to cut into each other or to approach so closely as to materially weaken the card. By interstaggering the adjacent columnar index point positions on the card in this manner a greater quantity 60 of statistical or tabular data can be placed thereon without increasing the length or width thereof.

On account of this interstaggered arrangement of the perforated positions I prefer 70 to use a novel form of sensing means which will now be described. Referring to Fig. 2, the record cards 10 are passed through the machine by the usual feeding rolls 13 past contact blocks 14, which in the embodiment 75 shown in Fig. 2 are arranged in two rows and interstaggered relatively to each other as shown in Fig. 3. Cooperating with these contact blocks are brush members 15 and 16 which are preferably of a blade type. The 80 blade brushes 15 cooperate with one row of index point perforations and blade brushes 16 cooperate with the adjacent interstaggered row. The breadth and character of these blades is such that each blade can properly drop into its corresponding column of index point perforations. However, such blade will not drop into the interstaggered perforation in the next adjacent column 85 since the blade must ride over the material 90 remaining between the perforations in said adjacent columns. For example, a brush which is adapted to cooperate with the perforation 12 will not cooperate with the perforations 17 in the adjacent columns since 95 it must ride over the intervening material 18.

In the modification shown in Figs. 4 and 5 a single row of brushes 15^a are provided and these brushes are arranged to be displaced both laterally and vertically when they are to cooperate with one or the other in staggered rows or columns of perforations. To effect a horizontal displacement the brush mounting 20 is provided with a pin and slot support 21. To effect a vertical displacement there is also provided a vertical adjusting screw 22.

It is not essential here to describe the

brush circuit arrangements. As herein shown there are individual contact blocks 14 for each column in the card. It is obvious that the contact members may be made common and circuit leads extended to individual insulated brushes.

This application is a division of my co-pending application, Serial No. 601,931, filed November 18, 1922. I do not claim in the 10 present application the novel card per se since this forms the subject matter of the parent application above referred to.

What I claim is—

1. In a machine for sensing perforated records, a plurality of series of sensing elements arranged one series in advance of and staggered with reference to the elements of the other series, and a series of contact blocks for each series of sensing elements.
2. In a machine for sensing perforated records, a plurality of series of contact blocks arranged one series in advance of and staggered with reference to the blocks in the other series, and a plurality of sensing elements for cooperation with said blocks.
3. In a machine for sensing perforated records, a plurality of series of contact blocks arranged one series in advance of and

in staggered relation to the blocks in another series, a series of sensing elements for each series of contact blocks, said elements being arranged with the contact points of one series in advance of and in staggered relation to the contact points of another series, and means for feeding perforated record material between said blocks and said contact points.

4. In a machine for sensing perforated records, a plurality of groups of sensing elements arranged one group in advance of and staggered with reference to the elements of the other groups, and the elements of the several groups overlapping the elements of other groups and a series of contact blocks 45 for each group of sensing elements.

5. In a machine for sensing perforated records, a plurality of groups of contact blocks arranged one group in advance of and staggered with reference to the blocks 50 in the other groups and the blocks of the several groups overlapping the blocks of other groups and a plurality of sensing elements for cooperation with said blocks.

In testimony whereof I hereto affix my 55 signature.

FRED M. CARROLL.
